UNITED STATES PATENT OFFICE.

ALBERT A. KAMIN, OF CHICAGO, ILLINOIS.

KNOCKDOWN HOUSE.

1,263,068.

Specification of Letters Patent. Patented Apr. 16, 1918.

Application filed April 19, 1916. Serial No. 92,127.

To all whom it may concern:

Be it known that I, ALBERT A. KAMIN, a citizen of the United States, and a resident of the city of Chicago, in the county of 5 Cook and State of Illinois, have invented a certain new and useful improvement in Knockdown Houses; and I do hereby declare that the following description of my said invention, taken in connection with 10 the accompanying sheet of drawing, forms a full, clear, and exact specification, which will enable others skilled in the art to which is appertains to make and use the same.

My invention relates generally to improvements in knockdown houses, and it consists, essentially, in the novel and peculiar combination of parts and details of construction, as hereinafter first fully set forth and described and then pointed out in the 20 claims.

This invention refers to knockdown houses for camping purposes, the use of consumptives, for living out of doors in the open air, and the like; and its object is the 25 production of a simple, cheap, and efficient structure which can be easily and quickly assembled by the merest tyro, and readily knocked down for shipment, occupying when so disassembled but little room, and 30 being capable of being packed in a crate or a box of little compass.

In the drawings already mentioned which illustrate this invention very fully, and form a part of this specification, Figure 1 35 is a vertical longitudinal or transverse section of my invention, the plan of which is, preferably, square in outline. Fig. 2 is a plan of my said invention. Fig. 3 is an elevation of one of the end roof rafters and 40 side wall plates assembled. Fig. 4 is an edge view of said rafter, showing the means of fastening the same to the side frames. Fig. 5 is an elevation of the ridge rafter, spacers, and rafter-locking means. Fig. 6 45 is an elevation of a detail of construction. Fig. 7 is a plan thereof.

Like parts are designated by the same characters and symbols of reference in all the figures.

50 In these drawings A, designates the house in its entirety, and B, the floor thereof. This floor comprises a plurality of separate sections mounted upon marginal scantlings C, and a medial scantling C^a. These marginal scantlings C, project beyond the edges 55

of the floor B, so as to afford a continuous ledge 10, along the four edges thereof, and upon these ledges the walls of the house are erected. These walls, which comprise two side, and two end walls, consist each of a 60 plurality of frames or panels D, consisting each of a, preferably paneled, base board 11, a top rail 12, two side members or stiles 13, and an intermediate horizontal rail 13^a. The 65 openings in these panels are closed by typical wire screens 14; or when the house is to be weather-proof, by filling panels, some of which may be glazed to allow light entering the inclosure.

The side and end walls are secured to 70 the marginal scantlings C, in the following manner:

To the base board 11, near the lower margin thereof there is fastened a connector comprising a metallic plate 15, best seen 75 in Figs. 6 and 7, said plate being vertically disposed and terminating in a round, bar, which is offset at the plate and has a downwardly extending shank 16, ending in a horizontal member 17, thereby forming a 80 hook, the object of which will hereinafter appear.

Into the outer edges of the marginal scantlings C, and registering with the position of the plate 15, are placed a corresponding number of elements, preferably metallic screw-eyes 18, or a like media, into the openings of which the shanks 16 are passed, so that, when the walls are in erected position, the hooks 17 will engage the under sides 85 of the elements 18, and thereby prevent upward and lateral movement of the wall panels D. The relative position of the shank 16 to the plate 15 is such that as the panels D are being raised, their inner faces 90 are forced against the vertical edges of the floor, thereby affording a practically tight joint between the floor and the walls. The outer adjacent vertical edges of the panels D are either tongued and grooved, or are 100 ship-lapped together as indicated in Fig. 2.

Let it be assumed, that the left and right portions shown in Fig. 2, and the top and bottom portions in Fig. 2, are the sides of the building, there is placed upon the panels 105 D of the side walls, wall-plates E, Fig. 1, comprising a strip of wood, the under side of which is grooved to embrace the upper margins of the top rails 12; said wall plates being, however, shorter than the length of 110

the sides of the building by one width of a wall plate, the object of which will herein-after appear.

Upon the upper margins of the end walls, 5 are erected roof-members F, Fig. 3, which comprise two inclined rafters 19, 20, which are connected at their lower ends to the ends of a wall plate 22, similar in construction to the wall plates E. At the ends of the rafters 10 and the wall plate 22, there are provided metallic gusset plates 23, bolted to the rafters and extending downwardly at 24, to embrace the wall plate 22 at its ends and the top rail 12 of the end wall panels, to which 15 these gussets are screw-connected, as at 24^a, Figs. 3 and 4.

The rafters 19, 20, are connected by a tie strip 25, medially of their length, and from the middle of these tie strips, and reaching 20 to the wall plate 22, there is a king post 26. On the inner face of this king post is secured a metallic bar 27, which extends downwardly beyond the wall plate 22, by an offset portion to the inner face of the top rail 12, at which 25 point a bolt 28, having a thumb nut, is passed through this plate and said top rail to make a rigid connection between the rafter-structure F and the middle of the end walls. At the peak 21, the rafters are gained 30 or notched for the reception of a ridge pole 29. This ridge pole has on its under side spacing blocks 30, which fit between adjacent rafters to maintain distance; and to securely connect these rafters to the ridge pole, there 35 is placed on the under side of the spacing blocks 30, adjacent a pair of associated rafters, a slidable bolt 31, which is constructed to engage looped bars 31^a, removably secured to the meeting ends of the rafters. By 40 sliding this bolt in the proper direction, the rafters are locked together, while moving the bolt in the opposing direction, they are released from the ridge pole when it is desired to dismount the building.

45 In addition to the combined rafters and wall plates at the ends of the structure, there are provided a plurality of intermediate rafters, spanning the side walls of the house; but these comprise only the inclined rafters 50 19^a, 20^a, with their ties 25^a. The lower ends of these intermediate rafters are notched, as at 32, Fig. 1, to rest upon, and abut against, the side wall plates E. There are of these intermediate rafters as many as necessary, 55 their number depending upon the length of the building. Ordinarily they may be spaced three feet apart, which is sufficient to support a roof, such as will be hereinafter described. On the inner faces of these rafters, 60 at the lower ends thereof are fixed one leg of angles 33, the other leg depending therefrom contacting with the inner face of the top rail 12, of the side walls. And through these lower legs, and through the top rails 65 12, there are passed bolts 34, which are pro-

vided with thumb nuts 34^a, which when screwed up, will securely fasten the angles 33 to the top rails 12, and with them the roof rafters. And it may be noted that the connecting and disconnecting of the roof structure F is accomplished without the use of a screw wrench or other tool, by the employment of bolts having thumb nuts, as shown. 70

The bolts 34 have downwardly extending portions which are formed into hooks 35, the 75 object of which will further on appear:

Through the house, adjacent the side and end walls, extend a plurality of horizontally disposed rods 36. These rods pass through the opposing corner panels D of the side 80 walls and the corresponding corner panels of the end walls respectively; and they are, on the exterior of these walls, provided with thumb nuts 37, which when screwed up will render the entire structure firm and rigid 85 in every direction. On the sides of the vertical members 13, of the panels D there are provided loops 38, which by preference, and for reason of adaptability and economy, may be the common steel screw eyes of commerce, 90 through which the rods 36 are passed, thereby assisting in maintaining the alinement of the panels D, and resisting inward as well as outward movement thereof under wind and other stresses. On the upper and lower 95 of these rods 36 may be arranged sliding curtains, not shown, whereby occupants of the house may be protected from the sun, wind, and rain; and when these curtains are employed, the weight of which when wet in 100 case of rain, will be considerable, I "spring" these rods over the hooks 35 on the bolts 34, hereinbefore described.

The roof proper of this house is preferably constructed of water-proof duck or 105 canvas 43, cut to proper shape and stitched together; and this roof is then stretched over the rafters and the ridge pole. The marginal edges of this textile roof are provided with spaced-apart gromets; and on the outer 110 edges of the wall plates E and 22, there are arranged equally-spaced turn buttons 39, which engage the gromets and securely hold the roof, and the gable-portions of the roof fabric in position. 115

For the purpose of entrance to, and exit from, the house, I provide the same with a door 40, Fig. 2, which also serves as one of the wall panels D. To produce this door, I fix a narrow strip 41, preferably at a corner 120 of the house, which strip is rabbeted. I then provide the vertical side member 13 of the adjacent wall panel with hinges 42, Fig. 2, to which the door 40 is connected, whereby the desired result is accomplished in a neat 125 and workmanlike manner.

I have hereinbefore mentioned that the wall-plates E at the sides of the structure are shorter than the length of the building 130 by one width of a wall plate, which is nec-

essary to bring the corners of the walls in close contact with each other, the end wall plates 22 being of a length equal to the width, out-to-out, of the structure.

5 To erect this portable structure, the floor sections B are placed upon the scantlings C, C^a, the screw-eyes 18 placed in proper position, and the side panels D placed flat upon the ground adjacent the floor, the hook portions of the connector placed into the eyes of the members 18, the wall plates E and the roof structures F located on the top rails 12 and properly secured as heretofore described, and then the walls raised to vertical position, which causes the hooks 17 to rotate in the eyes 18 and to engage the underside thereof. Now the rods 36 are placed in position, the medial rafters located properly, the ridge pole placed and locked to the rafters, and finally the fabric roof applied, when the building is ready for occupancy, the entire erection being accomplished in a very short space of time, by a mere tyro, it being understood that all the parts entering into the construction of this portable house have been completed at the factory, and assembled as far as possible, and shipped in the knocked-down condition, properly crated, to the place of erection.

30 I have hereinbefore stated that the plan of the building is a square, *i. e.* that the sides and ends thereof are of equal length; but it is obvious that this is not essential and that an oblong building can be constructed 35 and erected in substantially the same manner as heretofore described.

Having thus fully described this invention, I claim as new, and desire to secure to myself by Letters Patent of the United 40 States:

1. A portable knock-down house, including, in combination, a floor, scantlings underlying said floor, said scantlings projecting beyond the margins of said floor to afford a continuous ledge around the edges of said floor, a plurality of elements projecting from the outer edges of said scantlings, said elements having through-apertures, a series of upstanding panels constructed to rest upon said ledges, metallic connectors at the lower edges of said panels, said connectors including plates fastened to said panels, said plates terminating in a round shank having an offset adjacent said plate, said shank terminating in a hook, said hook being constructed to enter the apertured element when the panels are in horizontal position and to rotate in said apertures and to engage the lower surface of said element when said panels are being raised to vertical position, wall-plates at the upper margins of said panels, and horizontally disposed tie-rods connecting the opposing side and end walls.

2. A knock-down house, including, in combination, a floor, scantlings underlying said

floor, said scantlings projecting beyond the margins of said floor to afford a continuous ledge around the edges of said floor, a plurality of elements projecting from the outer edges of said scantlings, said elements having apertures, a series of upstanding panels constructed to rest upon said ledges, connectors at the lower margins of said panels, said connectors including metallic plates fastened to said panels, said plates terminating in an offset, round shank, said shank having a bar at right angles to said shank to afford a hook, said hook being constructed to enter the apertured element when the panels are in horizontal position, and to rotate in said apertured element and to engage the lower surface thereof when said panels are being elevated to vertical position, wall plates at the upper edges of said panels, horizontally disposed tie rods at the upper and lower ends of said panels connecting the opposing side and end walls, and metallic loops on the inner faces of said panels, said loops engaging said tie rods to prevent inward and outward movement of said panels.

3. A collapsible, portable building, including, in combination, a floor, said floor having depressed edges around its four margins, a series of matched-together panels forming the four walls of said building, said walls including two side and two end walls resting upon said edges, wall plates on two opposing side walls, a roof structure on the opposing end walls, said roof structure including wall plates on the latter end walls, rafters removably fixed to the latter end plates, means on said rafters connecting them to the end walls, connectors at the lower margins of all the walls, and members on said floor connecting with said connectors in such a manner that when said walls are being raised from a horizontal to a vertical position, said walls will be locked to said floor by said members.

4. In a knock-down building, the combination, of a floor, upstanding, matched-together, side panels upon said floor, grooved wall plates at the upper ends of said side panels, said wall plates embracing said panels at their upper ends, upstanding, matched-together end panels upon said floor, a roof structure on said end panels, said roof structure including grooved wall plates embracing the upper ends of said end panels, inclined rafters movably secured at their lower ends to the latter wall plates, a ridge pole at adjacent ends of said rafters, spacing blocks below said ridge pole, slideable bolts secured to the under side of said spacing blocks, and loops secured to the under side of adjacent ends of said rafters, and adapted for engagement by said sliding bolts.

5. In a knock-down building, the combination, of a floor, upstanding, matched-together side panels mounted on said floor,

- 4
- grooved wall plates at the upper ends of said side panels, said wall plates embracing the upper ends of said side panels, upstanding, matched-together end panels on said floor, a 5
- 5 roof structure on said end panels, said roof structure including grooved wall plates embracing the upper ends of said end panels, inclined rafters removably secured at their lower ends to said wall plates, a ridge pole 10 at the adjacent ends of said rafters, spacing blocks below said ridge pole, means secured to said spacing blocks and said rafters for locking said rafters together, the means for securing the rafters to said wall plates including a pair of gussets at each end of said 15 rafters, one of the ends of said gussets being permanently secured to said rafters, the other ends of said gussets being removably secured to said end panels.
- 20 6. In a portable knock-down house, the combination, of a floor, oppositely located side panels erected upon said floor, wall plates at the upper ends of said side panels, end panels mounted upon said floor, and a 25 roof structure on said end panels, said roof structure including inclined rafters, a wall plate removably secured to the lower ends of said rafters, a tie bar connecting coating rafters, a king post medially of said tie bar 30 and said wall plate, and means at the lower end of said king post for removably securing said king post to said end walls.
7. In a portable knock-down house, a base, side and end walls removably located on said 35 base, and a connector for securing said walls to said base, said connector comprising a metallic plate, said plate terminating at its lower end in a round rod, said rod being offset at its junction with said plate, the lower end of said rod being bent at right angles, 40 and an element on said base wherewith said right-angled portion engages to lock said walls to said base when said walls are in erected position and to permit said walls being removed when said walls are turned 45 down to horizontal position.
8. In a structure of the nature described, a floor, a ledge around the marginal edges of said floor, said ledge having a vertical wall, spaced-apart elements projecting from the 50 margins of said floor, said elements having through-openings, walls mounted on said ledges, said walls comprising each a series of separate panels, each of said panels having at its lower end a connector constructed to 55 enter said through openings when said panels are in horizontal position with their bottom edges free from said vertical wall, wall plates at the upper ends of a multiplicity of said panels to connect the same and 60 permit the panels being raised to vertical position, thereby causing the connectors to rotate in said through openings to force the inner lower margins of said walls against said vertical shoulders to afford tight joints and 65 to prevent lateral and upward movement of said walls.
- In testimony that I claim the foregoing as my invention, I have hereunto set my hand.
- ALBERT A. KAMIN.
